UNITED STATES PATENT OFFICE

2,501,981

AUTOMATIC TENSION CONTROL

Clayton E. Wyrick, Miami, Fla., assignor to The Egy Register Company, Dayton, Ohio, a corporation of Ohio

Application May 17, 1945, Serial No. 594,322

8 Claims. (Cl. 242—75)

1

This invention relates to a manifolding or a collating machine wherein a plurality of paper webs are assembled in adjacent relationship with the form faces printed upon the webs disposed in proper alignment with respect to one another so that the plurality of webs can be folded upon one another in an accordion fashion.

It is an object of the invention to provide a manifolding or collating machine adapted to receive a plurality of supply rolls of paper webs that are to be fed through the machine, and to provide braking mechanism to retard the rotation of the supply rolls should the paper webs have the tendency to discharge from the supply rolls at a greater rate than they are being used within the machine.

Another object is to provide a web or strip handling machine wherein a single element is operable to disconnect the driving power and effect application of the brakes.

A still further object is to provide a supply-roll braking means wherein the brake is applied with a snap action immediately upon disconnection of power, so that excessive slack due to momentum of the supply roll is prevented.

A further object is to provide, in a machine using a plurality of rolls, a brake mechanism for each roll together with means whereby the brakes are simultaneously controlled and applied with uniform force to all rolls.

Another object of the invention is to provide a machine of the character described that is smooth in operation and that may be quickly started and stopped, whereby increased efficiency and time saving over prior machines of a like type, is effected.

Other objects and advantages of my invention will become apparent as the description proceeds.

Figure 1 is a perspective view of the machine, wherein the brakes for the several supply rolls are manually controlled.

Figure 2 is a horizontal sectional view taken substantially on the line 2—2 of Figure 1.

Figure 3 is a side elevation of the supply-roll braking device, taken substantially upon line 3—3, Figure 2, and showing the brake shoe applied to the supply-roll drum.

Figure 4 is a view corresponding to Figure 3 but showing the brake in released position.

Figure 5 is an enlarged detail view of the machine looking in the direction of the arrow 12, Figure 1, and showing the motor mounting, motor and main shaft drive.

Figure 6 is an enlarged sectional plan view taken substantially upon the line 6—6, Figure 2, 55

2

showing the main drive clutch and clutch release, together with the brake actuating mechanism, and

Figure 7 is a perspective view of the clutch release mechanism and its interrelation with the brake operating means.

Referring particularly to Figure 1, the frame 110 has a platform 111 bolted to one of the uprights thereof. Main driving motor 112 is secured to platform 111 in any suitable manner and has a pulley 113 on its shaft. A switch 112a and cable 112b, Figures 1 and 5, are provided to control the motor. A belt 114 drivingly connects pulley 113 with a drive pulley 115, journaled upon a main drive shaft 116. Shaft 116 is journaled at its left end, as seen in Figure 6, in anti-friction bearing 117 carried by one of the cross braces of the frame 110, and at its right end in a plain bushing 118 within aligned apertures in a plate 119 and a reinforcement 120 secured thereto as by bolts and nuts 121. Plate 119 is supported from the two upright frame members at the right side of the machine, by end plates 122 secured to said frame members and to plate 119, as by angles and bolts to form a substantially rectangular bracket projecting horizontally from the right side of the machine, as will be clear from inspection of Figures 1 and 2.

The spaced horizontal side members 110a of frame 110 project rearwardly, as at 100, Figure 1, and are notched to form horizontally spaced pairs of supports for respective web-supply rolls A'. The shaft 176 of each roll carries brake drums 179 fixed thereto and a brake shoe 180 is provided for each drum and operated by mechanism subsequently described.

A brake rod 138 is mounted for vertical sliding movement upon the members 110a at one side of the machine. This mounting may conveniently take the form of slots 190 in rod 138, through which extend headed pins 191 secured in members 110a in vertically aligned positions. At its lower end rod 138 carries a pin 141 riding within a notch or slot formed in a foot brake lever 142. This lever 142 is pivoted to a rear frame member 110, as at 143, Figure 1, and is urged upwardly into brake-applying position, by a spring 144 fixed at one end to said lever and at the other end to an adjacent side member 110a. A guide bracket 145 is secured to the right front frame member 110 and confines the forward portion of lever 142 to substantially vertical movement.

Referring to Figure 6, pulley 115 has secured thereto, as by bolts 123, one element 124a of a friction clutch 124. The other element 124b of

said clutch, is splined or slidably keyed to shaft 116 in any suitable manner not shown. One or both of the adjacent clutch faces of parts 124a and 124b may have a friction facing 125 whereby they are drivingly coupled when forced into engagement with each other by spring 130.

Clutch element 124b has a hub 126 and collar 127 formed therewith to define a clutch-release channel 128 between them. A bevel pinion 129 is keyed to shaft 116 and a compression spring 130 surrounds said shaft and acts between a thrust washer 131 and collar 127 to urge clutch part 124b into contact with 124a. A bell crank 132 is mounted upon a shaft 133 journaled between end plates 122. Said bell crank is positioned below shaft 116 and its upright end 132a is forked and carries aligned rollers 132b riding within channel 128 whereby, when pivoted clutch element 124b is moved axially of shaft 116 against the force of spring 130, to separate the clutch faces and disconnect the driving power between pulley 115 and shaft 116. A shaft 134 is journaled by and between plate 119 and frame 110 upon an axis that, as seen at Figure 2, is perpendicular to shaft 133. A hand lever 135 is pinned to shaft 134 as at 136 and is so positioned as to contact the generally-horizontal arm 132c of bell crank 132. Referring to Figure 1, one side plate 122 is notched, as at 137, to form rests determining, respectively, the closed and open positions of clutch 124. Thus, by moving lever 135 downwardly, bell crank 132 is pivoted to open the clutch and stop the machine; and the clutch may be held open by moving lever 135 laterally until it engages beneath the horizontal step of notch 137.

It will be understood that this form power-driven feed or gripper rolls (not shown) are provided to draw the paper webs from the supply rolls A. Power for driving these rolls is supplied by a vertical shaft 170 journaled in bearings 139 carried by brackets attached to frame 110. At its lower end, shaft 170 has a bevel pinion 174, meshing with pinion 129. A step 146 is formed in said bracket so that, when lever 142 is forced downwardly to brake-releasing position, it may be given a slight lateral motion beneath said step whereby to hold it in said position.

Referring to Figure 4, a bell crank 147 is pivoted on a stub shaft 148 carried by side member 110a adjacent drum 179; and it will be understood that a similar arrangement of parts is provided for each web supply roll brake drum. The upright arm 147a of bell crank 147 has the shoe 180 fixed thereto at 149. A spring 150 is connected between the free end of horizontal arm 147b and adjacent member 110a to urge bell crank 147 in a counterclockwise direction of rotation. This rotation is resisted by a pin 151 in rod 138 that contacts the upper edge of arm 147b. Spring 153 engaging arm 152 on the rod 138 urges the rod 138 in an upward direction. Thus springs 150 act singly, each to apply its respective brake, and jointly to urge rod 138 into raised, or brake-applying position. Thus, in the position of lever 142, Figure 1, the brakes are all applied and the machine is at rest while, when said lever is thrust downwardly, the brakes are simultaneously released and held in such position.

As seen from Figures 6 and 7, shaft 134 carrying clutch-actuating lever 135, extends to the left through, and has a bearing in, an appropriate side member 110a. Said shaft terminates closely adjacent and at one side of brake rod 138 and

5 has journaled thereon, a latch 157 of a form clearly shown at Figure 7. Said latch is provided with a projection 154 to which is attached one end of a tension spring 155. The other end of spring 155 is attached to a pin on member 110a, whereby the latch is urged to counterclockwise rotation about shaft 134. At its free end, the latch has a nose adapted, under urge of spring 155, to snap over a pin 171 on rod 138 when said rod is moved downwardly to brake-release position and thereby hold the brakes released.

10 An arm 158 is fixed to shaft 134 adjacent latch 157 and has pivoted thereto near its free end, as at 172, a finger 156, notched at its free end to engage a pin 159 on latch 157. A tension spring 173 interconnects the adjacent ends of the arm 158 and finger 156, as clearly shown at Figure 7, and urges the finger to clockwise rotation which rotation is prevented, when the parts are in the position shown at Figure 4, by engagement between the notched end of finger 156 and pin 159. A pin 160 is fixed to rod 138 just below finger 156 so as to engage said finger 20 and pivot it counter-clockwise when the rod is raised to effect application of the brakes.

25 The conjoint operation of the clutch 124 and brake-actuating mechanism will now be clear. Suppose that the machine is at rest with the brake parts substantially as shown at Figure 3 and clutch lever 135 held in clutch-opening position by the notch 137 and that the desired number of supply rolls 179 have been positioned in brackets 100 and the webs have been threaded through the machine. Lever 135 may now be released and allowed to move upwardly thus permitting spring 130 to close clutch 124. Lever 142 is pushed down to correspondingly move rod 138. As said rod is moved downwardly, pin 171 rides up the slope of the nose on latch 157 and causes slight clockwise pivoting thereof. At the same time pin 160 moves down with rod 138 and permits spring 173 to rotate finger 156 downwardly until one surface of its notched end rests on pin 159 on latch 157. Simultaneously, springs 40 153 are being tensioned and as soon as pin 151 strikes arm 147b, bell crank 147 is pivoted clockwise and brake shoe 180 is separated from its drum. As soon as pin 171 rides past the nose on latch 157, said nose, under urge of spring 155, snaps over the pin while, at the same time pin 159 comes to rest within the notch at the end of finger 156. The parts are thus held in position as shown at Figure 11. The motor 112 is now started to superpose the webs and fold and stack them in the requisite manner.

45 When it is desired to stop the operation of the machine, lever 135 is pressed downwardly to open clutch 124 and disconnect the power drive to shafts 116 and 170. At the same time, rotation of clutch lever shaft 134, correspondingly rotates arm 158 and thus causes finger 156 to rotate latch 157 through the intermediary of pin 159. As soon as latch 157 has been rotated clockwise 50 so that its nose clears pin 171, spring 153 acts to raise rod 138 and its pin 151, and permit spring 150 to apply the brake shoe 180 with a snap action substantially simultaneously with the disconnection of power at clutch 124.

55 While the foregoing description has been confined, in the interests of clarity, to a single supply roll and brake mechanism therefor, it will be understood that each supply roll bracket 100 on the machine, is provided with a similar brake mechanism and that all of them are con-

trolled and simultaneously applied and released by movement of rod 138. Since each brake is applied by respective springs 150, it will be clear that all rolls are braked in a smooth, uniform manner.

It will be noted, that while clutch lever 135 is operable to set the brakes, they can be released only by downward movement of lever 142, thus making it unnecessary to lock lever 135 in clutch-opening position, as by engagement beneath step 137. If desired, a switch in the circuit of motor 112 and in series with switch 112a, can be provided, to be closed only when rod 138 is in brake release position to thus prevent inadvertent starting of the motor when the brakes are applied. In any event, operation of lever 135 has no effect upon the brake mechanisms when the brakes are set because, at this time, the pin 160 is holding finger 156 upwardly, out of contact with pin 159, as clearly shown at Figure 3.

By the foregoing construction, the web supply rolls are brought to a standstill simultaneously with opening of the clutch 124 whereby the building up of excessive slack or loops of the supply web is prevented and the operation of the machine speeded up and its over-all efficiency greatly augmented.

While I have described the embodiment of my invention as now preferred by me, numerous modifications and substitutions will be obvious to those skilled in the art and I desire to have it understood that the apparatus shown is merely illustrative, and that changes, modifications and substitutions may be made when desired within the scope of the claims appended hereto.

Having thus fully described my invention, what I claim as new and desire to secure by Letters Patent, is:

1. In a machine for continuously feeding a plurality of webs from a plurality of supply rolls to a mechanism for operating upon the webs, a shaft for rotatably supporting each said roll, a brake surface affixed to each said shaft, a power drive connected to draw said webs from said rolls and including a releasable clutch and actuating means therefor, brake means for each said shaft, means urging said brake means independently into engagement with said surfaces, means movable between a first position preventing engagement by any of said brake means, to a second position permitting independent engagement of the brake means, and means operated by movement of said actuating means to clutch-releasing position to effect movement of said movable means from said first to said second positions.

2. In a machine for drawing a strip of elongated material from a supply roll having a braking surface, and operating upon said material, a frame adapted to rotatably support said roll, feeding means adapted to engage said strip and draw the same from said roll, a power drive connected to operate said feeding means and including a disconnectable clutch, lever means operable to disconnect said clutch, brake means movable on said frame into and out of contact with said surface, yielding means urging said brake means into contact with said surface, a rod shiftable on said frame into one position holding said brake means out of contact with said surface, a latch operable to releasably hold said rod in said one position, and a connection between said lever means and latch to release said rod on disconnection of said clutch.

3. In a machine for drawing a web of material from a supply roll, a frame adapted to rotatably

support said supply roll, said roll having a brake surface, brake means pivoted on said frame for movement between a first position in contact with said surface and a second position out of contact with said surface, spring means urging said brake means into first position, a brake rod slidably adjacent said brake means and having a pin engageable with and holding said brake means in said second position, means urging said rod in a direction to move said pin out of engagement with said brake means, a latch on said frame, a second pin on said rod, said latch being engageable with said second pin on said rod to hold said brake means in second position, a power drive on said frame operable to draw material from said roll, said drive including a clutch, a shaft for operating said clutch, said shaft being connected to operate said latch whereby said rod may be released and said brake moved to first position.

4. In a machine for drawing a continuous web from a supply roll having a brake surface thereon, a frame adapted to rotatably support said roll, a power drive on said frame adapted to engage and withdraw a supply of web from said roll, said drive including a clutch, control means operable to render said clutch effective and ineffective to transmit power, brake means pivotable on said frame into and out of contact with said surface, and connections between said control means and said brake means, operable to apply said brake means in sequential relation with movement of said control means to render said clutch ineffective.

5. In a machine for withdrawing an elongated strip of material from a supply roll having a brake surface connected to rotate therewith, a frame adapted to rotatably support said roll, brake means pivoted on said frame, resilient means urging said brake means toward braking engagement with said surface, actuating means on said frame reciprocable from a first position to a second position engaging and holding said brake means released, spring means urging said actuating means into said first position, a latch pivoted on said frame and resiliently urged to engage and hold said actuating means in said second position, an arm pivoted adjacent said latch, and a finger pivoted on said arm and adapted to engage and move said latch as said arm is pivoted, to release said actuating means and permit application of said brake means.

6. In a machine for operating upon strips of material wherein the material is drawn from supply rolls, in combination, a plurality of rolls each having a braking surface, a bell crank pivoted adjacent each said brake surface, a brake shoe on each bell crank engageable with its respective brake surface, a spring urging each bell crank to brake-engaging position, a brake rod slidably to simultaneously engage all said bell cranks and pivot them to brake releasing position, means resiliently urging said rod away from brake-releasing position, and manually releasable means operable in one position to hold said rod in brake-releasing position against the action of said resilient means.

7. In a machine of the type described, a brake surface connected to control a rotatable roll of supply material for said machine, a brake shoe mounted for movement into and out of contact with said surface, resilient means urging said shoe into contact with said surface, a slidably rod having means preventing said contact in one position of said rod, spring means slidably

urging said rod out of said position, a pivoted latch adapted in one position to engage and hold said rod in brake-releasing position, means resiliently urging said latch into said one position, an arm pivoted adjacent said latch, a finger pivoted on said arm, a spring urging a notch on said finger into contact with a pin on said latch, means on said rod engaging and holding said finger out of contact with said pin when said rod is slid out of said one position by said spring means, and means operable to pivot said arm to operate said latch and thus release said rod and effect substantially instantaneous application of said shoe.

8. In a machine for withdrawing a strip of material from a rotatable roll thereof, a power drive operable to engage and withdraw said strip and including a disconnectable clutch, brake means operable to inhibit rotation of said roll, resilient means urging said brake means into effective position, a rod movable from a first position preventing operation of said resilient

10

15

20

means to a second position permitting operation of said resilient means, a latch operable to releasably hold said rod in first position, a manually operable device connected to disconnect said clutch and also release said latch in sequential relation to effect application of said brake means, and a lever for moving said rod to said first position whereby said brake means is rendered ineffective.
